UNITED STATES PATENT OFFICE.

CHARLES THOMPSON, OF PORTLAND, OREGON.

MECHANICAL TOY.

1,113,587.

Specification of Letters Patent.

Patented Oct. 13, 1914.

Application filed July 23, 1913. Serial No. 780,657.

To all whom it may concern:

Be it known that I, CHARLES THOMPSON, a citizen of the United States, residing at Portland, in the county of Multnomah and 5 State of Oregon, have invented certain new and useful Improvements in Mechanical Toys, of which the following is a specification.

This invention relates to an improvement 10 in mechanical toys, and particularly to mechanical bears, and has for its objects means adapted to give the bear a life-like appearance, causing it to rear upon its hind legs, sit up, fall upon all fours, shake its head 15 and growl. It is also provided with means for coughing up nuggets and similar articles.

I accomplish these objects by means of the 20 improvements illustrated in the accompanying drawings, in which—

Figure 1 is a sectional elevation of the bear on all fours. Fig. 2 is a top view of the operating mechanism shown in Fig. 1. Fig. 3 shows the bear in a sitting posture. Fig. 4 shows the bear standing on its hind 25 legs.

Like parts, throughout the several views, are referred to by similar reference characters.

Referring to the drawings in detail, a bear 30 pelt 1 is shown mounted on a wire frame 1^a which is attached to a pivot plate 1^b pivotally mounted on vertical standards 3 at 3^a. Standards 3 are rigidly mounted on horizontal levers 54 pivotally attached to a bracket 35 57 at 58 and held up by springs 56. Said bracket 57 is rigidly attached to the lower side of a floor 2 which is provided with an orifice 2^a through which standards 3 extend in such manner as to carry the bear above 40 said floor as shown. The upper ends of standard 3 are provided with slide bearings 4 adapted to receive vertical slide bars 6 which are pivotally attached at its lower end to a horizontal lever 53 at 55 and may 45 be raised or lowered by means of said levers 53, which are pivotally attached to bracket 57 at 59. Lifting arms 8 pivotally mounted on swinging arms 34 at 33 are attached at their outer ends to a circular band 9 carrying 50 the forward portion of wire frame 1^a and at their rearward end are pivotally attached to slides 6 and 7. Said swinging arms 34 are pivotally mounted on standards 3 at 5. Attached to circular band 9 are 55 springs 10 carrying depending arms 11 to which foot bars 12 are pivotally attached

at 13. Said foot bars 12 are hingedly attached at their lower ends to the inside of the bear's front paws at 14.

The hereinbefore described mechanism 60 constitutes the means used to bring the bear into a sitting or standing position, or will bring it down onto all fours as shown. In order to make the bear's hind legs slide forward when bringing it to a sitting position, 65 rollers 68 are provided. Said rollers are mounted on wires 69 attached to pivot plate 1^b, springs 51 having extensions 51^a attached to wires 69 and to brackets 50 in such manner as to draw the hind legs back into position shown in Fig. 1, when the bear is made to stand or fall on all fours. To bring the bear into a sitting position, as shown in Fig. 70 3, the lever 54 is first lowered and then lever 53 is lowered. To cause the bear to stand up, as shown in Fig. 4 only, lever 53 is lowered, lever 54 remaining in uppermost position. The flexible connections of the front legs causes them to fall into their proper positions through force of gravity. 75

In order to move the bear's head, it is mounted on a mechanism consisting of extension bars 30 attached to raising bars 8 and having swinging bars 18 pivotally mounted thereon at 17. Said horizontal 80 85 swinging bars 18 are provided with slide bearings 19 adapted to carry horizontal slide bars 16 having their inner ends bent downwardly at 16^a and their outer ends hingedly attached to slide bar extensions 21 at 20. Said slide bar extensions 21 are hingedly attached to the inside of the bear's head at 22, as shown. Springs 15 are held between the end of raising bars 8 and the downwardly bent ends 16^a of slide bars 16 90 95 so as to hold the head forward. Extension bars 32 are attached to raising bars 8 and are adapted to carry pivot bars 28 pivotally attached thereto at 29 and carrying slides 27. Head raising bars 24 are pivotally attached to slides 27 at 26 and to the inside of the bear's head at 23. Springs 25 are placed between bars 18 and 28 to hold the head in a normal position. 100

To raise the head, cords 70 are attached to slide 27 and pass over pulleys 71 through the body and thence through the hind legs to a convenient point below the floor. By pulling these cords, head raising bars 24 are forced forward and upward so as to raise the head. 105 Cords 63 are attached to ends 28^a of bars 28 and pass around the pulleys 63^a in such man- 110

ner that they can be used to move the bear's head sidewise by pulling upon them as desired, the head swinging upon pivot points 17 and 2. The lower jaw of the bear is pivotally mounted at 66 and is held in closed position by means of spring 67, but may be opened by pulling upon cord 64 attached to the lower jaw at 65 and passing over a pulley 72.

10 When using the bear for exhibition purposes it may be found desirable to use a live cub bear in connection therewith, and therefore to make the mechanical bear appear more natural it would be advisable to provide teats 47 connected by means of tube 46, to a milk reservoir 62 provided with a weighted plunger 61 to force the milk up to said teats. A cord 60 is used to raise said plunger 61 so as to remove the pressure on the milk if desired. In order to make the bear useful as an advertising medium it can be made to cough up gold nuggets or similar articles as premiums or discounts for goods purchased. For this purpose a nugget tube 36 provided with a filler opening 35 is so disposed within the body of the bear as to slope slightly downwardly toward the head and is provided with an extension 36^a reaching to the mouth and connected with the tube 36 by a contracted rubber tube 48. Said rubber tube 48 prevents the nuggets from falling out, but will allow them to be coughed out when air is forced into the rear end of the nugget tube 36 through air hose 39 connected with an air supply source and regulated by valve 52. To raise the bear's back when coughing a flexible plate 39 is fastened to the inside of the back and may be forced upward by means of bar 40 pivotally mounted on bell crank 42 which is mounted on arm 8 at 43 and may be actuated by means of cord 44 attached to the bell crank at 45.

40 What is claimed, is—

1. A mechanical bear comprising a frame, a pelt mounted on said frame, a pivot plate attached to said frame, vertical standards adapted to pivotally carry said pivot plate, horizontal actuating levers attached to the lower ends of said standards so as to raise or lower the standard, raising and lowering bars horizontally disposed within said frame, a circular band adapted to attach the forward end of said frame to the ends of said raising bars, swinging arms mounted at the top of the aforesaid standards and adapted to carry said raising bars at a point intermediate of the ends thereof, slide bearings attached to said standards so as to receive vertical slide bars pivotally attached at their upper ends to the rearward ends of said rais-

ing bars and at their lower ends to lifting levers, all so arranged as to raise said bear to a sitting or standing position or lower it to all fours, substantially as described.

2. In a mechanical bear having a frame, a pelt covering said frame and raising bars horizontally disposed within said frame and pivotally attached near the rear thereof so that the forward ends may be raised, horizontal extension bars attached to said raising bars, horizontal pivot bars pivotally mounted on said extension bars and provided with slide bearings, horizontal slide bars adapted to slide within said slide bearings, springs held between said slide bars and the aforesaid raising arms, hinge members hingedly attached at the forward ends of said slide bars and also hingedly attached to the inside of the bear's head, lower pivot extensions attached to the forward ends of said raising bars, pivot bars having projecting operating arms pivotally mounted on said lower pivot extensions, slides adapted to slide on said last mentioned pivot bars, short bars pivotally mounted on said last mentioned slides and attached to the inside of the bear's head, and springs vertically disposed between said last mentioned pivot bars and said first mentioned slide bars and means for actuating said mechanism so as to raise or lower the bear's head or turn it from side to side.

3. A mechanical bear comprising a frame, a pelt mounted on said frame, teats protruding therefrom, a tube connected with said teats, and also connected with a milk containing cylinder, provided with a weighted plunger adapted to force the milk through said tube and teats.

4. A mechanical bear comprising a frame, a pelt mounted on said frame, a feed tube provided with a filling opening and adapted to hold small articles, an extension tube connected with said feed tube by means of a contracted rubber tube and leading to the mouth of said bear, an air supply hose connected with said feed tube and an air supply source and means for admitting the air from said air supply source into said air hose and thence into and through said feed tube and extension in such manner as to force articles from said feed tube through said contracted rubber tube and through said extension tube to the bear's mouth.

In testimony whereof I affix my signature in the presence of two witnesses.

CHARLES THOMPSON.
